HOT-LINE TIE-IN TOOL

Benjamin F. Smalley, South Gate, Calif.

Application June 1, 1948, Serial No. 30,419

4 Claims. (Cl. 140—122)

1

This invention relates to a hot-line tie-in tool for twisting insulator tie wires around line wires and for similar purposes.

It is among the objects of the invention to provide an improved tool which will quickly and securely wrap or twist a tie wire on an insulator around a line wire, which is completely insulated so that it can be used on fully-charged line wires without danger to the operator, which cannot become accidentally disassociated from the line wire while in use, which has separable rotatable parts that can be separated and rotated only under predetermined conditions to avoid damage to the tool, which is light in weight so that it can be used without undue fatigue on the part of the operator, and is simple and durable in construction and economical to manufacture.

Other objects and advantages will become apparent from a consideration of the following description and the appended claims in conjunction with the accompanying drawings, wherein:

Figure 1 is a longitudinal elevation of a hot-line tie-in tool illustrative of the invention;

Figure 2 is a longitudinal elevation of the tool illustrated in Figure 1 showing the opposite side of the tool from that shown in Figure 1;

Figure 3 is a longitudinal elevation of the tool shown in Figure 1 showing a side of the tool at ninety degrees from the side shown in Figure 1;

Figure 4 is a top plan view of the tool illustrated in Figure 1;

Figure 5 is a longitudinal medial cross-section of the upper or winding head portion of the tool and is taken substantially on the line 5—5 of Figure 4;

Figure 6 is a transverse cross-section of the upper portion of the tool taken substantially on the line 6—6 of Figure 4; and

Figure 7 is a transverse cross-section taken substantially on the line 7—7 of Figure 4.

With continued reference to the drawings, the improved tool comprises an elongated tubular stem, generally indicated at 10, a winding head, generally indicated at 11, secured to one end of the stem 10, a driving head, generally indicated at 12, secured to the opposite end of the stem, and a drive shaft 13 extending through the stem and operatively connecting the driving head 12 to the winding head 11. Stem 10 and drive shaft 13 are preferably formed of a suitable, electrically insulating material so that the tool may be used to work on a fully-charged or hot line without danger to the operator.

The tool also generally includes manually operated means 14 extending from a location adjacent

2

the driving head 12 to the winding head 11 to operate the winding head for receiving and releasing a line wire about which a tie wire or other wire is to be wrapped or twisted by the tool.

The driving head 12 comprises a rigid, rectangular frame 15 one side of which is secured to the corresponding end of tubular stem 10 by a ferrule 16, a bevelled gear 17 journaled in the stem attached side of the frame and drivingly connected to the corresponding end of drive shaft 13, a transverse shaft 18 journaled in the frame, a hand crank 19 on one end of shaft 18 and a bevelled gear 20 on shaft 18 meshing with bevelled gear 17 so that drive shaft 13 will be rotated upon rotation of hand crank 19. A generally cylindrical handle 21 is secured to the side of frame 12 opposite the side secured to stem 10 and extends in a direction opposite the stem.

When in use the tool is held by one hand grasping the handle 21 and operated by the other hand rotating the crank 19.

In the winding head 11 a U-shaped frame 22 has its bight portion secured to the corresponding end of stem 10 by a ferrule 23 and has spaced-apart, substantially-parallel legs 24.

Each leg 24 of frame 22 has a semi-circular socket 25 formed therein adjacent its outer end and a respective, semi-circular bearing half 26 is secured in each socket with its straight side flush with the adjacent edge of the corresponding leg.

Each bearing half 26 has an outwardly extending, semi-circular flange or shoulder 27 on each end thereof for a purpose presently to be described. A pair of jaws 28 are positioned, one at the outer side of each frame leg 24 and these jaws are pivotally connected to the frame by the projecting ends of a shaft 29 extending transversely through the frame and journaled in the legs 24.

Each jaw 28 is provided with a semi-cylindrical socket in which is secured a bearing half 26 similar in all respects to the bearing halves secured in the sockets 25 of the frame legs. When the jaws are closed with the corresponding frame legs, as illustrated in Figure 4, the bearing halves 26 constitute two-spaced-apart, complete bearings in the outer end of the frame 22.

The two identical halves or parts 30 of a longitudinally split, tubular shaft 31 are journaled in the two bearings provided by the bearing halves 26 and are provided with shouldered collars 32 which operatively overlie corresponding end flanges or shoulders 27 on the bearing halves 26.

to maintain the two parts of the split shaft in operative association with the bearing halves.

A semi-cylindrical, flanged half collar 32' is secured on each end of each shaft part 30 and from each half collar 32' a wire twisting finger 33 inclines outwardly to engage the tie wire next to insulator and wraps the tie wire around a line wire received in the split tubular shaft 31.

The jaws 28 are opened and closed to separate and close the two parts 30 of the tubular shaft 31 by the manually operated means 14 and to this end a bracket 34 is secured at its ends to the respective jaws 28 and has at a location substantially midway between the jaws an outwardly extending tongue 35 apertured at its outer end to receive a pivot pin 36 pivotally connecting a link 37 to the outer end of the bracket. A ring 38 is clamped around the ferrule 23 and provides at one side of the ferrule an apertured fulcrum 39. A bell crank lever 40 is pivotally mounted in the fulcrum 39 by a suitable pivot pin 41 and has one end pivotally connected to the corresponding end of link 37 by pivot pin 42. An elongated rod 43 is pivotally connected at one end to the other end of the bell crank lever 40 by a pivot pin 44 and the opposite end of this rod is pivotally connected by a suitable connection 45 to one end of a bell crank lever 46 pivotally mounted by pivot pin 47 on a fulcrum 48 provided by a band 49 encircling the stem 10 near the driving head 12. A handle 50 is secured on the other end of bell crank lever 46 and when this handle is pulled downwardly, as illustrated in Figure 3, the bell crank lever 40 and bracket 35 are actuated to open the jaws 28 and thereby separate the two parts 30 of the split shaft 31. Obviously the two parts of the split shaft can be separated only when the plane of contact between the two parts of the shaft passes through the axis of shaft 29 by which the jaws 28 are secured to frame 22 as otherwise the interengaging shoulders 27 and 32 will hold the two parts of the shaft together.

When handle 50 is pulled down and the two parts 30 of split shaft 31 are separated the two parts of the split shaft may be placed around a line wire so that the line wire is received therein and when the handle 50 is subsequently raised and the two parts of split shaft 31 brought together, the line wire is positively retained in the split shaft against accidental removal therefrom and the split shaft as a whole is rotatable around the line wire so that the twisting fingers 33 may pick up the tie wire next to insulator and twist them around the line wire upon rotation of the hand crank 19.

Drive shaft 13 is drivingly connected to split shaft 31 through an axle pin 51 which has on one end a cylindrical ferrule 52 secured on the corresponding end of the drive shaft and has secured on its opposite end a bevelled pinion 53. Axle pin 51 is journaled in a bushing 54 which extends through the bight portion of frame 22 and is preferably provided as a continuation of ferrule 23 which may be formed of brass or some other suitable bearing material.

It is to be here noted that bevelled pinion 17 is secured on an axle pin similar to axle pin 51 journaled in a bushing provided in frame 12 and secured by a ferrule similar to ferrule 52 to the corresponding end of drive shaft 13.

Bevelled gear 53 meshes with a corresponding bevelled gear 55 secured on transverse shaft 29 and a spur gear 56 is secured on a reduced portion of shaft 55 and meshes with a split spur gear, generally indicated at 57, the two halves 58 of

which are respectively secured to the two halves 30 of split shaft 31. The parts of spur gear 57 are provided at one end with semi-annular shoulders 59 overlying corresponding shoulders 27 on one pair of bearing halves 26 to assist in operatively securing the two parts of the split shaft 31 to the bearing halves 26.

With the above described arrangement and with the jaws 28 closed with the frame legs 24 the split shaft 31 will be rotated when hand crank 19 is rotated.

Suitable locking means are provided to avoid damaging the tool by attempted rotation of the gear 57 when the jaws 28 are open. This means includes a transverse bar 60 secured to the frame and provided with an apertured tongue 61 and a locking pin 62 extending slidably through the apertured tongue in a position such that its lower or inner end is engageable between the gear teeth of the bevelled gear 53, as particularly illustrated in Figure 6. Pin 62 is normally held out of engagement with the teeth of gear 53 by a compression spring 63 surrounding the pin between tongue 61 and head 64 of the pin. When bracket 34 is actuated to open the jaws 28 and separate the two parts of split shaft 31 it contacts the head of pin 62 and forces the pin inwardly against the force of spring 63 until the inner end of the pin lockingly engages the teeth of bevelled gear 53 thereby precluding rotation of the twisting head gears while the jaws are open.

If desired, rod 43 of the manually operated means 14 may be held in close proximity to the stem 10 by a roller 65 journaled between the apertured ears 66 of a collar 67 surrounding stem 10 intermediate the length thereof which roller overlies the outer sides of rod 43 to hold the rod close to the stem at all times.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A hot-line tie-in tool comprising a stem, a shaft rotatable in said stem, a U-shaped frame secured on one end and a rectangular frame secured on the opposite end of said stem, two bevelled gears journaled one in each frame and drivingly connected to the corresponding ends of said shaft, a transverse shaft journaled in said rectangular frame, a hand crank on one end of said transverse shaft and a bevelled gear on the intermediate portion thereof meshing with the corresponding frame journaled bevelled gear, a handle on said rectangular frame opposite said stem, a second transverse shaft journaled in said U-shaped frame, a spur gear and a bevelled gear on said second transverse shaft, said bevelled gear meshing with the corresponding frame journaled bevelled gear whereby said spur gear is rotated upon rotation of said first-mentioned transverse shaft by said hand crank, a pair of jaws pivotally secured one to each leg of said U-shaped frame, a respective bearing half secured in each jaw and each frame leg constituting a pair of spaced-apart complete bearings when said jaws are closed with said legs, a split tubular shaft journaled in said bearings and having a pair of oppositely ex-

tending wire twisting fingers on each end thereof and adapted to receive a line wire therein, a split spur gear on said tubular shaft meshing with the spur gear on said second transverse shaft, a fulcrum at the stem end of said U-shaped frame, a bell crank lever pivoted to said fulcrum, a bracket secured to said jaws, a link operatively connecting said bracket to said bell crank lever, a rod extending from said bell crank lever, a second fulcrum adjacent said rectangular frame, a hand lever pivoted on said second fulcrum and operatively connected to said rod to open and close said jaws to separate and close the two parts of said split tubular shaft, and a locking pin carried by said U-shaped frame and moved by said bracket upon opening of said jaws to engage the corresponding frame journaled bevelled gear and lock the latter against rotation while said jaws are open.

2. A hot-line tie-in tool for twisting a tie wire about a line wire comprising an elongated tubular stem, a winding head on one end of said stem, a driving head on the opposite end of said stem, a drive shaft extending through said stem operatively connecting said driving head to said winding head, and hand operated means extending from adjacent said driving head to said winding head to operate said winding head to receive or release a line wire, said winding head comprising a U-shaped frame, a pair of jaws pivotally secured one to each leg of said frame, a longitudinally split tubular shaft journaled in said frame legs and said jaws and having outwardly extending winding fingers on each end thereof, gear means connecting said drive shaft to said split shaft, means operatively connecting said jaws to said hand operated means, and lock means carried by said frame and actuated by said hand operated means to engage said gear means and lock the latter against rotation when said jaws are open.

3. A tool for twisting a tie wire about a line wire comprising an elongated tubular stem, a drive shaft extending through said tubular stem and journaled therein, a winding head secured on one end of said stem, a driving head secured on the other end of said stem, and hand operated means extending along said stem from said winding head to a location adjacent said driving head for operating said winding head to receive or release a line wire, said winding head comprising a U-shaped frame having its intermediate portions secured to the corresponding end of said stem and having two legs extending away from said stem in spaced apart relationship relative to each other, a jaw pivotally secured to each of said legs, a half bearing secured to each leg, a half bearing secured to each jaw, the two half bearings carried one by a leg and the other by the jaw secured to such leg being complementary and together constituting a complete bearing and the two bearings provided by the four half bearings being spaced apart in a direction perpendicular to the longitudinal center line of said drive shaft, a split shaft journaled in said bearings and having a wire receiving bore extending longitudinally therethrough and winding fingers on each end thereof, a split spur gear on said split shaft between said bearings, a transverse shaft journaled in said bracket legs and disposed substantially parallel to said split shaft, a spur gear on said transverse shaft meshing with the spur gear on said split shaft, a beveled gear on said

transverse shaft, a beveled gear on the adjacent end of said drive shaft meshing with the beveled gear on said transverse shaft, and means connecting said jaws to said manually operated means.

4. A tool for twisting a tie wire about a line wire comprising an elongated tubular stem, a drive shaft extending through said tubular stem and journaled therein, a winding head secured on one end of said stem, a driving head secured on the other end of said stem, and hand operated means extending along said stem from said winding head to a location adjacent said driving head for operating said winding head to receive or release a line wire, said winding head comprising a U-shaped frame having its intermediate portions secured to the corresponding end of said stem and having two legs extending away from said stem in spaced apart relationship relative to each other, a jaw pivotally secured to each of said legs, a half bearing secured to each leg, a half bearing secured to each jaw, the two half bearings carried one by a leg and the other by the jaw secured to such leg being complementary and together constituting a complete bearing and the two bearings provided by the four half bearings being spaced apart in a direction perpendicular to the longitudinal center line of said drive shaft, a split shaft journaled in said bearings and having a wire receiving bore extending longitudinally therethrough and winding fingers on each end thereof, a split spur gear on said split shaft between said bearings, a transverse shaft journaled in said bracket legs and disposed substantially parallel to said split shaft, a spur gear on said transverse shaft meshing with the spur gear on said split shaft, a beveled gear on said transverse shaft, a beveled gear on the adjacent end of said drive shaft meshing with the beveled gear on said transverse shaft, means connecting said jaws to said manually operated means, and means on said split shaft engaging said half bearings restraining said split shaft against longitudinal movement relative to said bearings and restraining the parts of said split shaft against separation from said half bearings when said winding head is operated to receive a line wire therein.
